UNITED STATES PATENT OFFICE.

SAMUEL LAUFF, OF WATERBURY, CONNECTICUT.

QUICK-ACTION WRENCH.

1,136,540.

Specification of Letters Patent. Patented Apr. 20, 1915.

Application filed March 10, 1914. Serial No. 823,648.

To all whom it may concern:

Be it known that I, SAMUEL LAUFF, a subject of the Emperor of Austria-Hungary, and a resident of Waterbury, in the county of New Haven and State of Connecticut, have invented certain new and useful Improvements in Quick-Action Wrenches, which improvements are fully set forth in the following specification.

- 10 This invention relates to improvements in devices of that class available for manipulating nuts, suitably-headed bolts, and the like, and each thereof embodying a pair of jaws, one of which is adjustable, slowly 15 through the medium of coacting threads or quickly through the annulment of the coacting relation of said threads, toward and away from the other, such devices being well-designated quick-action wrenches.
- 20 The object of this invention is to provide a wrench of the character above indicated, which shall be simple and comparatively inexpensive as regards its construction; durable, efficient and reliable in practical service; 25 markedly convenient in its application to practical purposes, and which shall possess certain well-defined advantages over prior analogous devices.
- 30 The invention consists in the combinations, details and parts whereby, together with the novel disposition and relative arrangement of said parts, the attainment of the foregoing object is rendered practicable, all of which will be hereinafter more 35 specifically referred to and set forth in the appended claims.

The invention is clearly illustrated in the accompanying drawing, wherein—

- 40 Figure 1 is a side elevation of a quick-action wrench embodying my said improvements. Fig. 2 is a plan view, showing the same as it appears when turned obversely on its longitudinal axis ninety degrees from the position it is shown as occupying in Fig. 45 Fig. 3 is an enlarged detail view, the shank, including the fixed jaw conjoined therewith, being shown in side elevation, and the adjustable jaw, including certain parts supported thereby, being mainly 50 shown in central-vertical, longitudinal section, as along the broken line $x-x$ of Fig. 2. Fig. 4 is a view partly in rear elevation, and partly in cross-section, as along the 55 broken line $y-y$ of Fig. 1, of the movable-jaw extension. Fig. 5 is a view showing in

perspective and detached, the screw-controlling arbor made use of.

Having reference to the accompanying drawing, wherein similar reference-numerals denote like parts throughout the respective views, I make use, in carrying out my invention, of a stock or shank 2, fitted at one end thereof with a handle 2', at its opposite end with a fixed jaw 2'', and provided along its lower edge with segmental threads 3; also a jaw-extension 3', fitted with a jaw 3'', strapped to the shank 2, for movement to and fro therealong and as through the medium of upstanding yokes 4, 4', whereby the jaw 3'' becomes adjustable 65 relatively toward and away from the jaw 2'', and cut away from its under side upwardly, as at 4'', for the accommodation of a circumferentially threaded screw 5, the threads of the latter normally engaging the 70 segmental threads 3, and whereby the adjustability of the jaw 3'' relatively to the jaw 2'' may be effected and controlled, all as in common practice.

In practice it frequently becomes desirable that the extension 3', with the jaw 3'' carried thereby, may be oppositely adjusted between more or less distantly separated points along the shank 2, and independently 80 of the threads, respectively, aforesaid; and as a condition precedent to this end is the disengagement of the circumferential threads afforded by the adjusting-screw 5 from the segmental threads 3, or vice versa, 85 I loosely mount said adjusting-screw on a reciprocating arbor 5', which works longitudinally at its inner end in a socket 5'', formed in the extension 3', at the inner side of the screw 5, and in a bushing 5''', at the 90 opposite side of said screw, said bushing being pinned or otherwise fastened within an opening 6, formed in the extension 3' at the rear end-portion thereof, and in axial alignment with the socket 5''.

Arbor 5' varies diametrically in a manner 100 to insure the formation therefor of an annular shoulder 6', the inner end-portion thereof being of greater diameter than the remaining, or outwardly extending portion thereof, and said shoulder is, by preference, tapered, or generally inclined, from the circumference of the enlarged portion of arbor 5' to the circumference of the reduced portion thereof, this being advisable for a purpose which will more clearly hereinafter 105 110

appear. Arbor 5' projects more or less rearwardly from the extension 3', and is provided at its outer end with a terminal stop or disk 6''. Encircling the exposed portion 5 of the arbor 5', between the disk 6'' and a fixed element in advance thereof, as the bushing 5''', or rear face of the extension 3', there is interposed a spiral spring 7, whose tendency at all times is to elastically hold 10 the arbor 5' to the limit of its endwise play, rearwardly, and under which adjustment of the parts the adjusting-screw 5 occupies the aforementioned enlarged portion of said arbor, with its circumferential threads engaging 15 the segmental threads 3; while, upon said arbor being duly thrust endwise forwardly, against the tendency of the spring 7, said enlarged portion of the arbor 5', passing into the socket 5'', will be replaced relatively 20 to the adjusting-screw 5, by the reduced portion of arbor 5', under which condition of the parts clearance is provided whereby the adjusting-screw 5 may recede, or be caused to recede, from the shank 2 a 25 distance sufficient to insure disengagement of the circumferential threads aforementioned from the segmental threads 3, thus liberating the extension 3' and permitting quick adjustment thereof to and fro along the 30 shank 2, as will be readily understood. The arbor 5' being released for response to the action of the spring 7, that section of the reduced portion of said arbor now occupied by the 35 adjusting-screw 5 will be replaced by the enlarged portion thereof, the arbor moving endwise outwardly, thus causing the shoulder 6' to pick up the adjusting-screw 5 and urge the same in the direction of the shank 2 a distance sufficient to cause reengagement 40 of the segmental threads 3 by the circumferential threads afforded by said adjusting-screw, under which condition of the parts, as will be readily understood, the extension 3' may be adjusted to and fro along the 45 shank 2, only by duly turning the adjusting-screw aforementioned. The adjusting-screw 5 has a longitudinal bore 7', which coincides, approximately, in diameter with the diameter of the enlarged portion of the arbor 5', said bore being, by preference, duly flared at that end thereof adjacent to the shoulder 6', substantially as shown in Fig. 3. As will be seen, the inclining of the 50 shoulder 6' facilitates the picking-up, as above alluded to, of the adjusting-screw thereby, the attainment of this result being, incidentally, still further facilitated by flaring the bore 7', as stated. The 55

opening 6 is of sufficient diameter to permit passage of the arbor 5', with its enlarged 60 portion aforementioned, endwise therethrough, as in the operation of assembling the parts.

The practical operation of my present improved wrench will be apparent from the foregoing description thereof. It will also 65 be seen that the same is well adapted for the purposes for which it is intended, and further that the same may be modified to a considerable extent, particularly as regards the specific form of the reciprocating arbor 5', 70 the means availed of for elastically controlling the same, and various minor details of the general construction, without departing from the spirit and principle of my invention, as expressed and coming within the 75 scope of the claims hereto appended.

I claim:

1. A wrench comprising a segmentally threaded shank; a jaw-extension slidably mounted thereon; an arbor reciprocable axially only, varying in diameter for the formation therefor of an annular shoulder, and supported by said jaw-extension, the shoulder aforementioned being duly inclined; and a circumferentially threaded adjusting-screw, 80 said adjusting-screw loosely mounted on said arbor and adapted to be thereby controlled in a manner to releasably hold its circumferential threads in normal engagement with the segmental threads of the 85 shank aforementioned.

2. A wrench comprising a shank affording segmental threads; a jaw-extension having a cut-out for the reception of an adjusting-screw and provided at its rear end with an 90 opening and forwardly of said cut-out with a socket, the latter and said opening arranged in axial alinement and communicating, respectively, with the cut-out aforementioned; a bushing in said opening; a spring-controlled arbor arranged to reciprocate 95 endwise in said socket and bushing, traversing the cut-out aforementioned, and having an inclined, annular shoulder; and a circumferentially threaded adjusting-screw, the 100 latter loosely mounted on said arbor, within said cut-out, and adapted to be thereby controlled in a manner to releasably hold its circumferential threads in normal engagement with the segmental threads of the 105 shank aforementioned.

SAMUEL LAUFF.
